UNITED STATES PATENT OFFICE.

JOSEPH C. PRIMS, OF HORNELL, NEW YORK, ASSIGNOR TO THE A. J. DEER COMPANY, INCORPORATED, OF HORNELL, NEW YORK, A CORPORATION OF NEW YORK.

SLICING MACHINE.

Application filed June 18, 1920. Serial No. 389,793.

To all whom it may concern:

Be it known that I, JOSEPH C. PRIMS, a citizen of the United States, residing in Hornell, in the county of Steuben and 5 State of New York, have invented new and useful Improvements in Slicing Machines, of which the following is a specification.

This invention relates to a slicing machine and more particularly to the means 10 whereby the article to be sliced is fed forward to new parts thereof to the cutter as the slices are successively cut from the body of the article.

It is the object of this invention to provide simple, efficient and reliable means for 15 feeding the article to the cutting line which are so constructed as to permit of quickly and easily either advancing or retracting the article supporter and also wholly re- 20 moving the latter from the machine when the same is to be cleaned.

In the accompanying drawings:

Figure 1 is a top plan view of a part of a slicing machine equipped with my invention. Figure 2 is a rear end elevation of the same. Figure 3 is a fragmentary vertical transverse section, on an enlarged scale, taken on line 3-3, Fig. 1. Figure 4 is a fragmentary horizontal section taken 30 on line 4-4, Fig. 3.

Similar characters of reference refer to like parts throughout the several views.

The carriage or table of the slicing machine forming part of the means for presenting the article to be sliced to the cutter or blade which cuts the article into slices may be variously constructed but in the form shown in the drawings the same comprises a marginal frame 10 and a panel 35 11 secured to the central part of the frame by bolts 13 or similar means. This table may be reciprocated so that its front end moves back and forth relatively to a cutter, or the table may be fixed and the cutter 40 moved back and forth past the front end of the table beyond which the article to be sliced projects.

Above the table is arranged the supporting plate 14 upon which the article to be 45 sliced is fastened by holding or clamping means of any suitable and approved character which however form no part of the present invention.

The means containing my invention for 50 guiding the plate on the table and holding

the same normally against lateral displacement but permitting the plate to be readily removed for cleaning are constructed as follows:

15, 16 represent two longitudinal guideways arranged lengthwise on the upper side of the table adjacent to the opposite longitudinal edges, the guideway 15 being preferably flat and horizontal and the guideway 16 being constructed in the form 60 of a longitudinal groove which is preferably rounding in cross section, as shown in Figs. 2 and 3. On the underside of the supporting plate adjacent to one of its longitudinal edges the same is provided 65 with feet or bearing points 17 of fiber or similar material which slidably engage with the flat horizontal guideway 15 of the table and on its underside adjacent to its opposite longitudinal edge this plate is provided 70 with a longitudinal guide rib 18 which is preferably rounding in cross section and engages with the groove of the table. By this means the supporting plate will be guided in its longitudinal movement 75 on the table but held against lateral displacement so that the article supported on the plate will always be properly presented to the cutter and insure cutting uniformly thin slices. The radius upon which the 80 guide groove is formed is preferably less than the radius upon which the guide rib is formed so that when the rib engages the groove the lowest part of the rib will not touch the bottom of the groove 85 and thus permit the rib to constantly center itself in the groove and take up wear between the co-operating surfaces of the guide rib and groove without causing any looseness between these parts and avoiding 90 noise in operating the machine or uneven cutting of slices from the article on the supporting plate.

A downward pressure is constantly exerted against the upper side of the supporting 100 plate adjacent to that edge thereof which has the guide rib so as to keep the latter in proper engagement with the guide groove during the normal operation of the machine. The preferred means for this purpose shown 105 in the drawings comprise a presser plate or bar 19 mounted lengthwise on the table adjacent to the outer side of the guide groove therein and engaging with the upper side of the adjacent longitudinal edge portion 110

of the supporting plate. The outer longitudinal edge of the presser plate preferably rests upon a raised bead 20 on the table upon which the presser plate can turn vertically as a fulcrum while the inner edge of this presser plate bears against a longitudinal flange 21 projecting laterally from the supporting plate beyond the guide rib thereof. This presser plate is constantly pressed downwardly by tension means which in the present case comprise a plurality of upright bolts 22 arranged in a longitudinal row and passing through corresponding openings in the table and presser plate adjacent to the guide rib and groove, each of these bolts engaging the head at its upper end with the top of the presser plate and being drawn downwardly by a spring 23 which surrounds the bolt and bears at its upper end against the bottom of a recess or pocket 24 in the underside of the table while its lower end bears against the nut of this bolt, as best shown in Fig. 3.

As the article supporting plate slides forwardly or backwardly on the table the guide rib and groove between the same are held firmly in engagement with each other by this tension device and any wear between the same is automatically taken up thereby. When however, it becomes necessary to remove the supporting plate from the table for cleaning, inspection or repairing, this can be easily done by first lifting that edge of the supporting plate opposite its guide rib, as shown by dotted lines in Fig. 3, and then moving the supporting plate to the unribbed edge thereof when these members may be quickly and easily separated or dismembered for any desired purpose. Assembling of these members may be easily effected by manipulating the same in reverse order of that just described.

For convenience in manipulating the supporting plate the same is provided on its upper side adjacent to its opposite longitudinal edges with handles 25, 26.

The improved means for moving the article supporting plate lengthwise of the table in accordance with my invention are constructed as follows:

27 represents a screw threaded feed shaft arranged lengthwise and horizontally along that side of the table and supporting plate at which the rib and guideway between the same is located. This shaft is journaled in bearings 28, 29 on the adjacent part of the table so as to be capable of turning but held against lengthwise movement. This screw shaft may be turned in any suitable manner but in practice means are usually provided for turning the same forwardly either manually or automatically and also turning the same backwardly manually, but the mechanism for operating this shaft forms no part of the present invention.

Mounted on the screw threaded shaft is a shifting member which is operatively connected therewith. This member in the preferred construction has the form of a shifting member 30 having the form of a sleeve 70 which surrounds the screw shaft and is provided with an upwardly projecting boss 31 which contains a cylindrical radial guideway 32 opening at its inner end to the shaft while its outer end is closed. Within this cylindrical guide way, a cylindrical follower 33 is movable toward and from the screw and also turning in this guideway. 34 represents a shifting rod arranged in the cylindrical guideway and having its inner end connected with the follower while its outer part extends through the outer end of the boss and is provided externally of the latter with a finger piece or handle 35 for manipulating the same. The follower is 75 yieldingly held in engagement with the thread of the screw shaft by a spring 36 arranged in the cylindrical guide and engaging at one end with the bottom of said guide while its other end engages with said follower. When the latter engages the thread of the screw shaft than a turning movement of the latter causes the shifting member or sleeve to move lengthwise of the shaft but when the follower is withdrawn from the screw shaft then the rotation of the shaft does not affect the shifting sleeve and the latter may be moved lengthwise of the shaft to the desired position. For the purpose of retaining the follower in its operative 80 and inoperative position at will the outer end of the guide boss is provided with an elevated flat face 37 which is perpendicular to the axis of the shifting rod and at another part of the outer end of this boss the same is 85 provided with a recess 38. On its inner or underside the finger piece 35 is provided with a retaining pin or projection 39 which may be engaged with recess 38 and permit the follower to intermesh with the thread 90 of the screw shaft, as shown in Fig. 3, when it is desired to move the shifting sleeve by the rotation of this shaft. When however this sleeve is to be retained temporarily in disconnected condition from the screw 95 shaft then the shifting rod and follower are pulled outwardly by the finger piece until the follower is withdrawn from the thread of the screw shaft after which the finger piece is turned and its retaining pin 39 engages with the elevated face 37 of the boss whereby the shifting sleeve and shaft will be uncoupled.

In order to permit of moving the article supporting plate forwardly by the forward movement of the shifting sleeve the latter is provided with an inwardly projecting tappet 40 which is adapted to engage with an abutment 41 on the supporting plate, this abutment being preferably formed in 100

tegrally with the adjacent handle 26 of the supporting plate, as shown in Fig. 1. The contact surface of the tappet is preferably formed by means of a hardened screw 42 arranged in a threaded opening in the tappet and engaging the abutment.

For the purpose of guiding the shifting sleeve in its longitudinal movement and holding the same against turning relatively to the screw shaft this sleeve is provided with two guide arms 43, 44, projecting therefrom at an angle relatively to each other, and adapted to engage two longitudinal guide surfaces 45, 46 arranged at an angle relatively to each other on the table and associated parts, the guide surface 45 for the upper arm 43 being formed on the upper side of the presser plate 19 and the guide surface 46 for the lower arm 44 being formed on the outer side of the table, as shown in Fig. 3. To prevent noise and undue friction the guide arms 43, 44 are provided with contact plugs 47 of fiber or

the like for engagement with the guide surfaces, which plugs are seated in recesses in 25 the respective arms.

By means of the construction the article supporting plate may be freely removed from the table and reassembled therewith without disturbing the mechanism whereby 30 the same is moved lengthwise of the table.

I claim as my invention:

A slicing machine comprising a table having two longitudinal guide surfaces arranged at an angle relatively to each other, 35 an article supporting plate slidable lengthwise on said table and having an abutment, a screw threaded shaft journaled on the table, and a shifting member operatively connected with said screw shaft and having 40 a tappet engaging with said abutment and two guide arms arranged at an angle relatively to each other and engaging, respectively with said guide surfaces.

JOSEPH C. PRIMS.
